UNITED STATES PATENT OFFICE.

OLUF CHRISTIAN BÖCKMAN, OF NOTODDEN, NORWAY.

ELECTRICAL INDUCTION-FURNACE.

1,275,206.

Specification of Letters Patent. Patented Aug. 13, 1918.

Application filed May 3, 1918. Serial No. 232,272.

To all whom it may concern:

Be it known that I, OLUF CHRISTIAN BÖCKMAN, a subject of the King of Norway, residing at Notodden, in the Kingdom of Norway, have invented certain new and useful Improvements in Electrical Induction-Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the known type of electric induction furnaces the regulation of the load is carried out by regulating the tension of the electric current or by cutting in or out windings of the induction coils.

In several instances it is however desirable to regulate the load of an induction furnace independent of the current passing through the coils of the same, and in this case generally a very low $\cos. \phi$ for the furnace may be permitted.

This is obtained according to the present invention, two forms of which are diagrammatically illustrated on the drawing.

Figure 1 is a sectional view through a single phase induction furnace according to the present system, and Fig. 2 is a plan of a three phase induction furnace.

According to the invention the magnet core 1 is so constructed that the magnetic flux can either be conducted through the furnace or outside the same through a magnetic connection located in parallel to the magnetic connection of the furnace.

This, as illustrated on the drawing, may be obtained by means of a pivoted part 2 of the magnet core as illustrated on Fig. 1.

The coil 3 may be surrounded by a protecting shell 4 by means of which the coil according to the present construction is better protected in cases of leakage in the furnace than is the case with other induction furnaces.

In polyphase current furnaces according to the present system there is obtained the advantage that each phase may be regulated separately, which is often desirable

when the smelting channels have different cross-sections, so that the temperature in some channels become higher than in others. The furnace should be brick lined and provided with doors and tapping holes, and it may be mounted stationary or as a tilting furnace in any known manner.

It is clear that the invention may be carried out otherwise than in the manner illustrated on the drawing, and the invention is not limited to these modifications, the main feature of the invention being the arrangement of a regulable magnet flux path in the magnet system of the furnace.

I claim:

1. In an electric induction furnace the arrangement in parallel with the ordinary path of magnetic flux of a regulable magnetic flux path with the object of permitting regulation of the furnace temperature independent of the current and magnetic coils.

2. In an electric polyphase induction furnace the arrangement in each separate phase of the furnace of a regulable path of the magnetic flux in parallel to the ordinary magnetic flux path with the object of permitting regulation of each separate phase of the furnace, independent of the other phases and of the current and magnet coils.

3. In an electric induction furnace an induction coil, a core forming a closed path for the magnetic flux created by the said coil, said core comprising an extension outside the furnace and means for regulating the magnetic flux in said extension.

4. In an electric induction furnace an induction coil, a core forming a closed path for the magnetic flux created by the said coil an extension on said core outside the furnace, said extension comprising a pivoted member by means of which the path formed by the same may be closed or interrupted with the object of regulating the magnetic flux in the main core.

In testimony that I claim the foregoing as my invention, I have signed my name in presence of two subscribing witnesses.

OLUF CHRISTIAN BÖCKMAN.

Witnesses:

C. VORMAN,
THS. HERZ.
